UNITED STATES PATENT OFFICE.

PAUL MAUSER, OF OBERNDORF, GERMANY, ASSIGNOR TO THE WAFFEN-FABRIK MAUSER, OF SAME PLACE.

GUN-BARREL.

SPECIFICATION forming part of Letters Patent No. 451,768, dated May 5, 1891.

Application filed June 6, 1890. Serial No. 354,539. (No model.)

To all whom it may concern:

Be it known that I, PAUL MAUSER, a subject of the King of Würtemberg, German Empire, and a resident of Oberndorf-on-the Neckar, in the Kingdom of Würtemberg, Germany, have invented certain new and useful Improvements in Barrels for Breech-Loading Guns, of which the following is a specification.

10 In the accompanying drawings, which illustrate my invention as applied to a breech-loading gun, Figure 1 is a side elevation of a gun-barrel, showing a portion of the stock and breech-block in longitudinal section. Fig. 15 2 is a fragmentary side elevation of the central portion of the gun-barrel, showing the stock and fastening in longitudinal section, the view being on a somewhat larger scale than Fig. 1. Fig. 3 is a cross-section of the 20 barrel and stock, cut on the line 3 3 in Fig. 2 and looking in the direction of the arrow. Fig. 4 is a fragmentary side elevation of the back portion of the barrel, showing the fastening for the back sight in longitudinal section. Fig. 5 is a cross-section thereof, cut on the line 5 5 in Fig. 4 and looking in the direction of the arrow. Fig. 6 is a fragmentary side elevation of the front portion of the barrel, showing the forward end of the stock and the 25 fastening in longitudinal section. Fig. 7 is a cross-section of the barrel, cut on the line 7 7 in Fig. 6 and looking in the direction of the arrow; and Fig. 8 is a cross-section of the front end of the barrel, cut on the line 8 8 in Fig. 6 and looking in the direction of the arrow.

30 Heretofore the barrels of small-caliber breech-loading guns have been made uniformly tapering externally from the large swell at their back end, which contains the 35 seat for the projectile and cartridge and is screwed into the breech-case to the muzzle, and the barrels have been fastened to the gunstock by rings or by projections from the barrels which have been embedded in and fastened to the stock. In rapid firing the barrel becomes heated and therefore expands or lengthens. Heretofore its fastenings have not permitted it to lengthen when expanded by this heating, and the barrel therefore has

been bent or otherwise deformed. The consequence of this is that the gun loses its accuracy. In endeavoring to overcome this disadvantage the gun-barrel has been placed in a jacket, such as a pipe of thin sheet-steel, screwed at the back end to the back swell of 55 the barrel and extending thence forwardly and having a contracted front end engaging the front end of the barrel. This arrangement, however, did not allow the free lengthening of the barrel due to expansion, and it had the 60 further disadvantage that it either increased the weight of the arm, or, if the barrel was made correspondingly lighter, reduced its stability. The present invention aims to overcome these difficulties and produces a 65 gun-barrel which can expand and lengthen freely and is as stiff and strong as any ordinary gun-barrel of the same weight. It also provides improved means whereby the front and back sights can be easily mounted and 70 adjusted, and means whereby the back end of the barrel can be readily adjusted to the closing-bolt in case the tight joint at this place should have been destroyed by too frequent firing.

75 Referring to the accompanying drawings, let A represent the gun-barrel, B the gunstock, and h the breech-case. The barrel A has a back swell g, which has no faces, but is cylindrical and is screwed into the breech-case h, 80 and its remaining external surface consists of a plurality of portions of different sizes, each such portion being of uniform cross-section throughout its length. In the construction shown these portions are cylindrical and 85 of about equal length, the back portion a being of the necessary diameter to resist the bursting strain due to the explosion of the cartridge which is seated in the swell g. The front portion b of the barrel is throughout its 90 entire length preferably of as small a diameter as is usually used at the muzzle end only. At the point where the two portions a and b meet it is important to avoid sharp corners, and the transition from the surface of the one 95 portion to that of the other should be effected by a rounded shoulder. The barrel is closely fitted to the stock and is secured thereto by

fastening provisions, constructed to hold the parts together laterally, but to permit longitudinal movement of the barrel relatively to the stock. This is preferably accomplished by 5 two bands *d* and *e*. The band *d* is mounted directly over the junction of the barrel portions *a* and *b*, and is provided with an inner offset at its forward side which touches the portion *b*, while at its rearward side its inner 10 surface bears against the portion *a*, its inner surface being constructed to leave a free annular space in front of the shoulder between the portions *a* and *b*. A corresponding free 15 annular space is milled out of the wood of the gunstock, as best seen in Fig. 2, thus leaving a free annular space around the forward end of the portion *a* of the barrel, which construction allows the portion *a* to expand and lengthen freely under the band *d*. The band 20 *e* is near the muzzle of the barrel and its upper semicircular portion engages the portion *b* of the barrel, while its lower part engages the end of the stock, to the front face of which is fastened a metal plate *p*, fitting at its upper 25 part to the under side of the barrel. By this construction the barrel is firmly held to the stock by the band *e*, while it can expand and lengthen freely under the band and over the plate *p*. The plate *p* has a hole through 30 which the cleaning-rod *l* passes when it is placed in its seat in the stock. The fastening-band *e* is held to the stock by a spring-hook *e'* on the under side of the latter, which engages at its forward end with a notch in 35 the under side of the band *e*. The cleaning-rod *l*, when pushed into the gunstock, rests immediately over the spring-hook *e'* and prevents the inward movement of the latter, thereby locking it in engagement with the 40 band *e*.

In case the tight joint between the back end of the barrel *A* and the closing breech-bolt of the lock becomes impaired by frequent firing of the arm, this difficulty can be remedied 45 by removing the barrel from the breech-case by unscrewing it therefrom and then turning off sufficient material from the back face of the swell *g* to enable the barrel to be screwed home again into the breech-case until the 50 tight joint is restored. By doing this the barrel is turned more or less, owing to the fact that it is screwed farther into the breech-case than originally, so that the two gun-sights *m* and *k* will not stand directly at the 55 top of the barrel and it will be necessary that they be taken off and adjusted. If they were mounted in the usual way, this removal and adjustment would be a tedious and expensive alteration; but my present invention provides an improved construction for mounting 60 the gun-sights by means of which they may be easily and rapidly adjusted.

In the drawings, *k* is the front sight, and *v* is the back sight. The foot or support *k'* of 65 the front sight is provided with a ring *r*, which

is pushed upon and fits snugly over an offset or slightly-reduced cylindrical portion at the muzzle of the gun-barrel, where it is secured in the correct position, preferably by a set-screw, after which it is fixedly secured to the 70 barrel by soldering it thereto. The back sight *v* is carried by a tube-like foot or support *x*, which is pushed over the portion *a* of the barrel and secured in the correct position, 75 preferably by drawing together the split portion of the tube-like support *x* by the transverse screw *n*, thereby clamping it in place on the barrel.

If desired, instead of using the screw *n* for fastening the support *x* in place, the screw 80 *o*, which fastens the sight-spring to the support *x*, may be used to secure the latter to the barrel. After securing the support *x* to the barrel it is fixed in position by tin solder. Thus the parts are held firmly in 85 position. When, however, the barrel has been turned in restoring the tight joint between it and the breech-bolt, it is necessary to readjust the sights. This can then be easily done by slightly heating the barrel, which will melt 90 the solder, so that after loosening the securing-screws each of the sights may be turned to the new and correct position, where they can be again secured by tightening the fastening-screws. When the barrel cools down 95 sufficiently, the tin solder will harden and fix the sights to the barrel again.

My invention can be variously modified, but without departing from its essential features, and I do not limit myself to the specific 100 features of construction shown and described as constituting the preferred form of my invention.

What I claim is, in a breech-loading gun of small caliber, the following defined novel 105 features and combinations, substantially as hereinbefore set forth, namely:

1. In a small-caliber breech-loading gun, the combination, with the gunstock and the barrel constructed with two cylindrical portions *a* and *b* of different diameters, of the central band *d* for fastening the barrel to the stock, constructed with an offset to fit the two cylindrical portions *a* and *b* of the barrel, and constructed to leave a free space in the 110 front portion *a* of the barrel, and said stock constructed with a free space in front of the portion *a* of the barrel, whereby expansion 115 of the latter is permitted.

2. In a small-caliber breech-loading gun, 120 the combination, with the gunstock and the barrel constructed with a cylindrical front portion *b*, of a fastening between the barrel and stock, consisting of the front band *e*, constructed to fit at its upper part to the portion 125 *b* of the barrel, and the plate *p*, screwed to the stock.

3. The combination, with a gun-barrel having a cylindrical portion and a gun-sight therefor, of a fastening for securing said sight 130

to said barrel, consisting of a tube-like clamp carrying the sight and fitting closely over said cylindrical portion, and constructed to be clamped thereto.

5. 4. The combination, with a gun-barrel having a cylindrical portion and a gun-sight therefor, of a fastening for securing said sight to said barrel, consisting of a tube-like clamp

carrying the sight and fitting closely over said cylindrical portion and soldered thereto.

This specification signed by me this 26th day of March, 1890.

PAUL MAUSER.
